UNITED STATES PATENT OFFICE.

MAY W. FRANZHEIM, OF WHEELING, WEST VIRGINIA.

KITCHEN-SINK.

1,296,178.

Specification of Letters Patent.

Patented Mar. 4, 1919.

Application filed March 13, 1917. Serial No. 154,553.

To all whom it may concern:

Be it known that I, MAY W. FRANZHEIM, a citizen of the United States, residing at Wheeling, in the county of Ohio and State 5 of West Virginia, have invented a new and useful Kitchen-Sink, of which the following is a specification.

The device forming the subject matter of this application is a kitchen sink, and the 10 invention aims to provide a device of this kind including a back in which articles to be used in connection with the sink may be housed in accessible positions.

Another object of the invention is so to 15 locate the cabinet in the back of the sink with respect to the drain board, that the latter element, in addition to its usual functions, will prevent articles in the cabinet from falling accidentally into the sink.

20 Another object of the invention is so to construct the cabinet that the same, projecting rearwardly beyond the back, will carry the weight of the back, the sink and the drain board.

25 It is within the province of the disclosure to improve generally and to enhance the utility of devices of that type to which the present invention appertains.

With the above and other objects in view 30 which will appear as the description proceeds, the invention resides in the combination and arrangement of parts and in the details of construction hereinafter described and claimed, it being understood that 35 changes in the precise embodiment of the invention herein disclosed can be made within the scope of what is claimed, without departing from the spirit of the invention.

In the accompanying drawings:—

40 Figure 1 is a front elevation, parts being in section;

Fig. 2 is a vertical section through the cabinet.

In carrying out the present invention 45 there is provided a back 1 which may be equipped with a rearwardly extended flange 2. Projecting forwardly from the back 1 is a sink 3 which may be supported in part on legs 4. A drain board 5 extends between 50 one end 6 of the sink, the forward wall of the sink and the back 1. Extended between the forward wall of the sink, the bottom 11 of the sink, the back 1 and the inner end of the drain board, is an end wall 7 which coacting with the end wall 8 defines

the compartment 9 of the sink. Below the drain board 5, the sink preferably is open as shown at 10. The back 1 carries the usual cocks 12 discharging into the sink.

Assembled with the back 1 and ordinarily 60 formed integrally therewith is a rearwardly projecting cabinet 14 which may be pro-

vided with one or more shelves 15 adapted to receive articles used in or about a sink. Hinged as at 17 to the back 1 is a door 16 65

which constitutes a closure for the lower side of the cabinet 14, any suitable mecha-

nism 18 being supplied, whereby the door 16 may be held in a closed position. It is to 70 be observed that, as indicated at 20, the

cabinet 14 projects rearwardly beyond the rear edge of the back 1. The cabinet, there-

fore, is adapted to enter the plaster 19 or other support, and as a consequence, the 75 cabinet constitutes a means for sustaining

the weight of the articles in the cabinet, the weight of the back 1, the weight of the sink 3 and the weight of the drain board 5. The

drain board 5 exercises a double function in 80 that, in addition to its usual and well known function, it forms a shelf preventing the articles in the cabinet 14 from dropping ac-

cidentally into the sink 3 and being broken 85 therein.

Preferably, all parts of the structure 85 hereinbefore described, saving the door 16 and the legs 4, if the latter are used, are made integral, although this detail is not insisted upon.

It is to be observed that the door 16 90 swings above the drain board 5. As a consequence, articles in the compartment 9 of the sink will not be knocked over or injured when the door is swung to an open position.

Having thus described the invention, what 95 is claimed is:—

In a device of the class described, a back; 100 a sink projecting forwardly from the back;

a drain board projecting forwardly from the back and discharging into one end of the

sink; a cabinet projecting rearwardly from the back; and a horizontally swinging door 105 for the cabinet, the drain board being located at a slight vertical distance below the

cabinet and directly in front of the cabinet and the door, whereby the drain board will prevent articles in the cabinet from falling

into the sink, and the free vertical edge of 110 the door being substantially in vertical

alinement with the inner end of the drain board when the door is swung rearwardly into an open position against the back, whereby the drain board will prevent articles in the sink from being struck by the door, when the door is swung to an open position.

Copies of this patent may be obtained for five cents each, by addressing the "Commissioner of Patents, Washington, D. C."

In testimony that I claim the foregoing as my own, I have hereto affixed my signature in the presence of two witnesses.

MAY W. FRANZHEIM.
